UNITED STATES PATENT OFFICE.

LEON N. HAMPTON, OF NEW YORK, N. Y., ASSIGNOR TO WESTERN ELECTRIC COMPANY,
INCORPORATED, OF NEW YORK, N. Y., A CORPORATION OF NEW YORK.

ELECTRICAL PLUG SWITCH.

Application filed December 21, 1920. Serial No. 432,252.

To all whom it may concern:

Be it known that I, LEON N. HAMPTON, a citizen of the United States, residing at New York, in the county of Bronx, State of New York, have invented certain new and useful 5 Improvements in Electrical Plug Switches, of which the following is a full, clear, concise, and exact description.

This invention relates to electrical switch- 10 ing devices such as are employed in telephone central offices for testing separately the conditions of a subscriber's line within and without the exchange system.

In the majority of central offices at pres- 15 ent in use, a distributing frame is used to cross connect the outside portion of each subscriber's line with terminals corresponding to the subscriber's drop number. At this frame are located all the devices pro- 20 tecting the central office from dangerous current potentials and continued excessive currents. The protection usually employed against the latter consists of a pair of "heat coils" inserted between contact springs 25 suitably formed for the convenient inser- tion of the coils by the attendant test man. Distributing frames and "heat coils", being well known in the art, need no further description here. Plugs of the class to which 30 this invention relates are adapted to be inserted in place of such "heat coils" between the inside and outside line spring contacts and are connected by means of suitable con- ductors to the testing desk.

35 The object of the invention is to provide a plug of the character described which is of simple construction and is capable of easy manipulation on the part of the user.

To this end the plug is provided with a 40 pair of arms, one for each side of the line, each arm comprising a flat metal strip bent at one end to conform to the shape of the spring with which it contacts and a conductive block insulatingly supported by each 45 arm and provided with a contacting surface also shaped to conform with the contour of the spring with which it contacts. The two arms are supported on separate frame mem- bers to cooperate through a hinge joint hav- 50 ing a spiral spring which keeps the two arms resiliently held apart. The tendency in the arms to spread assists greatly in handling the plug. Suitable cord conductors are attached to the arms and the contact blocks

which they carry, by means of screws fasten- 55 ing through the cord tip lugs provided at their ends.

The invention will be understood more completely by reference to the drawing which shows its preferred embodiment. 60 Fig. 1 represents the plug in place contacting with the line springs of the distributing frame. Fig. 2 is a cross-sectional view taken at the plane 2—2. Fig. 3 is a perspective view with sections cut away to show 65 the internal construction of the hinge joint.

Referring to the drawings, the construc- 70 tion of the distributing frame is shown com- posed of the main vertical rib 1 supporting contact springs 2 at the end of which carbon 75 protector blocks 7 are supported against rib 1; springs 3 to co-operate with the end of the "heat coil" protector; and springs 4 also adapted to normally contact with "heat coils". The springs 2, 3 and 4 are bolted to 75 the rib 1 by means of bolts and insulated from each other by means of strips of in- 80 sulating material 6. At the end of the springs 4, a slot 8 is cut which cooperates with a projection at one end of the "heat coil" to hold it in place.

The test plug is composed of two flat 85 metallic arms 9 having free ends 10 that conform to the configuration of the ends of the springs 4; a pair of contact blocks 11 pref- 90 erably of metal supported on the arms 9 by means of screws 12 and insulated from the arms by strips of insulating material 13 and insulating collars 14 for the shanks of the screws 12; two stirrup supporting members 95 15 and 16 insulatingly supporting the arms 9 by means of screws 17 and the strip of insulating material 18; and a hinged joint 19 cooperating with the members 15 and 16 to allow relative rotary motion in the arms 9. 95

The hinge joint 19 has two concentric 100 rings, an inner ring 20 and an outer ring 21. The inner ring is provided with a groove 22 on its circumference into which is inserted a spiral spring 23 one end 24 of which is 105 bent so as to engage with the ring 20 in the notch 25 and the other end of which 26 is adapted to engage with the outer ring 21 at the notch 27. The end 24 projects beyond the outer edge of the ring 20 and to allow 110 a space for it to move freely, a portion of the outer ring 21 is cut away leaving aperture 38. The stirrup 15 is attached to the

outer ring 21 by means of screws 28 and the stirrup 16 is attached to the inner ring 20 by means of the screws 29.

Each of the contact blocks 11 is provided 5 with a stepped surface 30 so that a large area contact is made therewith by the springs 2 and 3. The knee in this stepped surface 30 also prevents the block from being easily displaced. At the break in the 10 surface 30 are two flanges 39 which fit on either side of the contact spring to laterally support the block in contact with the spring and to prevent turning of the plug in place. On each of the arms 9 are located 15 a pair of pegs 31 which cooperate with the groove 8 of springs 4 to prevent the plug from twisting out of position between the distributing frame springs.

The conductors 32 and 33 of the cord 34 20 are introduced into the plug through the space left between outer ring 21 and the bottom of the stirrups 15 and 16. These conductors are attached to the contact arm 9 and contact blocks 11 in any suitable 25 fashion, the preferred manner of fastening them being by means of screws 35 threaded directly into the contact member. The tie cord 36 of the cord 34 is attached to a loop projection 37 integrally formed 30 on the ring 21.

By virtue of the tension in the spring 23, the arms 9 tend to spread apart so that some slight pressure is necessary to be exerted on these arms to bring them together 35 sufficiently for insertion between distributing frame springs. This materially assists the user in performing this operation since one of his hands would naturally be holding his pliers and the "heat coils" which 40 have been removed from the frame. With the assistance of this tendency in the arms of the plug to spread, he can insert the plug with the use of only one hand.

What is claimed is:

45 1. In an electrical test plug, a pair of contact arms, each having a flat length and bent at one end to conform to the configuration of a distributing frame spring; and

a contact member insulatingly supported on the inner side of a portion of the flat 50 length of each said arm, and provided with a stepped contacting surface.

2. In an electrical test plug, a pair of contact arms, each having a flat length bent at one end to conform to the configuration 55 of a distributing frame spring; a contact member for each of said arms, each of said contact members being insulatingly mounted on the inner side of a portion of the flat length of the arm and provided with a 60 stepped contacting surface; and a hinged joint cooperating with said arms to permit relative movement between said arms.

3. In an electrical test plug, a pair of contact arms, each having an end portion 65 bent to conform to the configuration of a corresponding distributing frame spring contact; a contact member insulatingly supported on each of said arms and provided with a surface conforming with a 70 configuration of a corresponding distributing frame spring; a stirrup member insulatingly supporting each of said arms; and a hinged joint comprising a pair of concentric ring members, each of said rings 75 supporting one of said stirrup members, and a spiral spring interacting between the said ring members tending to keep the contact arms apart.

4. In an electrical test plug, a pair of 80 contact arms, a contact member insulatingly supported on each said arm, and provided with a stepped inner surface, and a flange provided on each side of said contact member.

5. In an electrical test plug, a pair of 85 contact arms, contact members insulatingly supported on said arms, a hinged joint for the arms, means upon the joint to partially limit the spreading or the closing of the 90 arms, and a spring member tending to spread the arms.

In witness whereof, I hereunto subscribe my name this 17th day of December A. D., 1920.

LEON N. HAMPTON.
